Specification for Design.

Patented July 29, 1919.

Application filed March 20, 1919. Serial No. 283,932. Term of patent 7 years.

To all whom it may concern:

Be it known that I, JOSEPH J. HOLSEN, a citizen of the United States, residing at Manitowoc, in the county of Manitowoc and State of Wisconsin, have invented a new, original, and ornamental Design for a Combination-Tool, of which the following is a specification, reference being had to the accompanying drawings forming a part thereof.

Figure 1 is a perspective view of the combination tool, showing my new design;

Fig. 2 is a top plan view of the same; and

Fig. 3 is an elevation of lefthand end of Fig. 1.

I claim:—

The ornamental design for a combination tool, substantially as shown.

In testimony, that I claim the foregoing as my own, I have hereto affixed my signature in the presence of two witnesses.

JOSEPH J. HOLSEN.
